UNITED STATES PATENT OFFICE.

CHARLES J. WALKER, OF GARY, INDIANA.

REINVENTION.

Application filed January 5, 1918, Serial No. 210,514. Renewed December 15, 1922.

To all whom it may concern:

Be it known that I, CHARLES J. WALKER, a citizen of the United States, and resident of Gary, in the county of Lake and State of Indiana, have invented certain new and useful Improvements in Riveters, of which the following is a specification.

This invention relates to machines used for riveting, punching, pressing, forging, or similar operations.

One object of my invention is the provision in machines of the type embodying relatively reciprocating members of a rotating driving mechanism constructed and arranged to utilize the fly wheel effect or inertia or the inertia and torque of the rotary driving mechanism in applying pressure to work positioned between said reciprocating members.

Another object of the invention is to provide a machine embodying relatively reciprocating work engaging members and a rotary driving mechanism having novel means enabling a substantially maximum pressure to be exerted on the work at all points in the approach of the relatively movable members.

Another object of this invention is the provision in a riveter having relatively reciprocating work engaging members and a rotary driving mechanism of novel means constructed and arranged to automatically shut off the motive power and enable the work to be completed by the inertia of the moving parts of the machine.

A still further object of this invention is the provision of a self-contained, motor driven, variable stroke riveter, constructed and arranged to deliver a maximum riveting pressure at any point in the working stroke or travel of its relatively reciprocable dies or rivet sets.

A still further object of my invention is the provision of an electrically driven riveter having the novel constructions, combinations and arrangements of parts shown in the drawings, to be more fully described hereinafter and to be particularly pointed out in the appended claims.

The drawings, forming part of this specification, illustrate embodiments of my invention and so much of the electric control as will give a clear understanding of the operation of the apparatus in connection with the following description.

Referring now to the accompanying drawings, Figure 1 is a side elevation, showing

a preferred form of riveter, constructed and arranged in accordance with my invention.

Figure 2 is a sectional side elevation, on a larger scale, showing details in the application of my invention to the riveter of Figure 1.

Figure 3 is a sectional plan showing the construction of the limit switches used on the motor with the apparatus of Figures 1, 2 and 3.

Figure 4 is a detail end elevation showing the arrangement of the feather keys on splines in the apparatus of Figures 1 and 2.

Figure 5 is an elevation, partly in section, showing my invention as embodied in a modified form of riveter.

Figure 6 is an inverted sectional plan showing details in the construction of the frame of my improved apparatus, the section being taken on the line 7--7 of Figure 5.

Figure 7 is an enlarged longitudinal section of the head of the machine and moving parts cooperating therewith.

Figure 8 is an enlarged detail plan of the deflection switch or cut-out shown, and adapted for use with apparatus constructed in accordance with my invention.

Figure 9 is an enlarged detail plan showing the construction and arrangement of the forward and reverse limit switches on the electric control used with the apparatus of Figures 4 and 5.

Figure 10 is a diagrammatic plan illustrating the motor operating and control circuits employed with the apparatus of Figures 1, 2, and 3.

Figure 11 is a plan, similar to that of Figure 10, showing the operating and control circuits used with the apparatus of Figures 4 to 8.

In the construction of Figures 1 to 4 of the drawings, the letter A, in a general way, designates the main frame of the riveter. This frame, which is of the horseshoe type, is a hollow casting of box section, which provides a very strong and rigid construction, and has integral stakes or jaws 2 and 3 forming a deep throat 4 therebetween, the open end of the throat being uppermost. The jaws are provided with feet 5, 5 by which the riveter is supported in upright position upon a suitable foundation or base. (The foundation not forming part of my invention, is not shown nor further described).

The jaw 2 of the main frame is provided

on its upper end with a suitable opening forming a socket in which the fixed or stationary die or rivet set 6 of the riveter is removably secured.

8 The opposing die or rivet set 7 of the riveter, which reciprocates and which is in axial alignment with the stationary rivet set 6 is removably secured in a suitable socket provided in one end of the horizontal translatory ram 8, this ram being operatively mounted on top of the jaw 3, in a manner hereinafter fully described.

13 As successive lots of the materials operated upon by the rivet sets 7 and 8 will vary in thickness, the length of the rivet sets, the sockets for the rivet sets, or one of them, may be changed to suit the thickness of the particular lot of material being operated upon.

18 The jaw 3 of the frame A is made somewhat shorter than the jaw 2 and is provided with an integral shelf or bracket 9 which, with the flat upper end of the jaw 3, forms the support for the translatory ram 8, rotary driving motor, designated generally by the letter B, and related parts of my improved apparatus.

23 The driving motor B includes a casing or housing 10 having an integral extension 11 on one end and is provided with a foot 12 and a pad or boss 13 by which the motor is secured in place upon the upper end of the short jaw 3 and bracket 9 of the riveter frame. (See Figures 1 and 2.) Pairs of stud bolts 14 and nuts 15 and the cap bolts 16 fasten the motor housing 10 on top of the jaw 3 and a key 17 is fitted into registering transverse keyways in the meeting faces of the foot 12 and jaw 3 to transmit end pressure from the motor housing 10 to the jaw 3 of the riveter frame and to prevent any shearing strain being put on the bolts 14 and 16 when the apparatus is being used.

28 The motor housing extension 11 has an axially horizontal opening or hole 18 therein, one end of this opening having a counterbore 19, and a bushing or sleeve 20 in the opening 18, which is preferably made of bronze, forms a bearing for the reciprocatory ram or plunger 8 of my improved riveter, the ram being shorter than the sleeve. (See Figure 2.) Short feather keys or splines 21, secured in keyways at the end of the housing extension 11 project through slots in the end of the bushing 20 into keyways 22 in the outer surface of the ram 8 at opposite points on the diameter thereof, to prevent rotative movement of the ram 8 and the bushing within the opening 18 in the housing extension 11. The cap screws 23, 24, which extend through holes in the housing extension 11 into screw threaded holes in the key 21 fasten the keys in operative position within the keyways. (See Figure 2.)

33 A circular head 24 is located within the motor housing 10 at the rear end of the housing, this head being secured in place by means of curved, segmental keys 25, the periphery of the keys extending into the circumferential groove or keyway 26 in the inner surface of the hollow motor housing 10 and cap screws 27, which extend through holes in the keys 25 into registering screw threaded holes in the head 24, maintain the head in place and hold the keys within the keyway 26. The inner face of the head 24 has a recess 28 and a counterbore 29 therein, which are in axial alignment with the opening 18 and its counterbored portion 19 in the motor housing extension 11. (See Figure 2.)

38 A ball bearing, formed of an annular outer race ring 30, an inner ring 31, and a series of interposed balls 32, is located within the counterbore 19 in the housing extension 11, and a similar ball bearing, of somewhat smaller size and formed of outer and inner race rings 33, 34, and interposed balls 35, is positioned within the counterbore 29 in the head 24. The ends of the armature shaft or quill 36 are rotatably mounted in these ball bearings.

43 Dust rings 37, 37 and 38, 38, for the quill or armature shaft 36 are provided within the counterbores 19 and 29, on opposite sides of the ball bearings, and an oil ring 39 on the quill 36 prevents lubricant from traveling lengthwise on the quill and coming into contact with the armature windings on the quill or hollow armature shaft 36.

48 The coils 40 and segmental commutator 41 of the motor armature are built up on the shaft 36 and the hollow motor housing 10 has pole pieces 42 and coils 43 thereon of any approved construction. A thrust bearing, which is formed of two hardened steel disks 44, 45, and an interposed phosphor bronze disk 46, is located within the recess 28 of the head 24 to transmit end thrust from the armature or quill shaft 36 to the head 24 in the operation of the riveter. Pins 47 in the end of the quill shaft 36 and in the bottom of the recess 28, which extends into recesses in the disks 44 and 45, serve to cause the disk 44 to rotate with the shaft 36 and to prevent rotation of the disk 45 in the recess 28.

53 The armature shaft or quill 36 has a recess of opening which extends axially inward from one end of the quill, and a bronze nut 48 is secured in said opening by a key 48a. This internally threaded nut preferably is provided with resistance threads 49, as shown, and screwed into the nut is the threaded shaft or translating-screw 50 by which the reciprocating plunger or ram 8 and rivet set 7 of the riveter are actuated in operating the apparatus. One end of the translating-screw 50 has an

unthreaded portion which extends into the recess 51 in one end of the ram 8, and a pin 52 which extends transversely through registering holes in the ram 8 and end of the translating-screw 50 fastens the screw to the ram and prevents rotative movement of the screw 50 relative to the non-rotating ram 8 during translatory movement of the screw and ram within the motor housing 10. 10 A disk 53 in the bottom of the recess 51 forms a bearing to transmit the end thrust of the shaft 50 on the ram 8, rotation of the ram 8, as has been explained, being positively prevented by means of the feather keys or splines 21 in the housing extension 11. 15

Limit switches 54 and 55 of the closed circuit type are provided on the riveter to control the extent of forward and backward or translatory movement of the ram 8 in its bearing or sleeve 20, these switches being conveniently located on the housing extension 11 and having longitudinally movable stems 56 extending through registering holes in the extension 11 and sleeve 20 into contact with the periphery of the ram 8. (See Figure 2).

The switch stems 56, which are moved in one direction by means of the coil springs 57 thereon, have a switch bar 58 which bridges the gap between the contacts 59,—59, and 60,—60, on the switches to complete the circuit through such switches. Notches 61 and 62 in the ends of the ram 8, when opposite the stems 56 of the switches enables each stem to be moved by its spring 57 so as to lift its contact bar 58 and open the switch of which it forms part, and break the control circuit, when the ram 8 reaches the end of its forward or backward travel, the appropriate notch 61 or 62 then being immediately opposite its cooperating switch stem 56 at such time.

It is, of course, possible for either of the switches 54 and 55 to fail to operate to open the electric circuit, and such occurrence ordinarily might cause jamming of the machine or even breakage or other serious injury. But in such event no trouble will result with the apparatus of Figures 1 and 2 because the position and length of the feather keys 21 relative to the ram 8, when the ram is at the limit of its extreme forward and backward stroke is made such as will permit of the ram 8 clearing the ends of the keys or splines 21 when the predetermined length of travel of the ram is exceeded and when exceeded the ram 8 will be free to rotate while the friction between the threads in the nut 48 and on the screw shaft 50 will be sufficient to cause the screw and ram to rotate with the armature shaft or quill 36.

In the modified construction illustrated in Figures 5 to 9, the main frame A, which

also is of the horseshoe type, has integrally joined vertical jaws 2 and 3, forming a throat 4 therebetween. The feet 5 on the frame A support the riveter in upright position on its foundation or base. (Not shown). The upper end of the jaw 2 is provided with a transversely extending opening forming a socket in which the fixed die or rivet set 6 of the riveter is detachably secured. 75

The movable die or rivet set 7, which is arranged to reciprocate or move toward and away from the fixed die or rivet set 6, is detachably secured in a die socket 68 and the tapering shank of this socket is secured in a correspondingly tapered opening in the end of the hollow ram or plunger 64 of the riveter of Figures 5 to 9, by means of a transversely extending key or pin 65. A bushing 66, preferably formed of phosphor-bronze provides a suitable bearing within the opening 67 in the upper end of the jaw 3 of the riveter frame for the translatory plunger 64, the key 68 preventing rotation of the bushing or bearing 66 within the opening 67. A spline or feather key 69 seated in a suitable keyway in the plunger 64 and sliding in a registering keyway 70 in the bore of the bushing 66 prevents rotation of the ram 64 within the bushing without interfering with translatory movement of the ram in the bushing. (See Figure 7).

A nut 71 also is secured within the opening in the upper end of the jaw 3, one end of this nut engaging with the shoulder 72 on the jaw 3 to take the end thrust of the screw shaft 73 in the working stroke of the ram 64. (See Figure 5). The key 68 for the bushing 66 also engages with and prevents rotation of the nut 71. 100

The nut 71, which is preferably formed of phosphor-bronze, has internal threads which engage with the external screw threads on the translating-screw or shaft 73 and the threaded end of this rotating shaft is fastened to one end of the ram or plunger 64, by a cap screw 74 which is screwed into the end of the shaft 73 and which is arranged to rotate with the shaft 73. 110

A thrust bearing formed of disks 75, 76 (or which may be of any of the various old and well known constructions,) is interposed between the recessed end of the ram or plunger 64 and connected end of the screw shaft 73 to transmit power from the screw shaft to the non-rotary ram. (See Figure 7). 115

The screw shaft 73 projects rearwardly through the nut 71 and the opening in the upper end of the jaw 3, and through a bearing 77 which is mounted on the upper end of the pedestal 78. 125

The pedestal 78 in turn is mounted on the shelf or bracket 79 which, as shown, is made separate from but is rigidly fastened on one 130

side of the jaw 3 of the horseshoe frame A. Obviously, however, the bracket and frame may be integrally formed.

Keyed or otherwise fastened on the screw shaft 73, between the jaw 3 of the riveter frame and the bearing 77 for the outer end of the shaft 73, so as to move therewith, is a spur gear 80, this gear moving sidewise in reciprocating with the screw shaft 73 and meshing with a wide faced pinion 81 which is fastened on the armature shaft 82 of the electric driving motor B. The face of the pinion 81 is made of sufficient width to remain in mesh with the spur gear 80 throughout out the operative lengthwise travel of translatory movement of the screw shaft 73, and of such width as to become disengaged from the spur gear at the extreme limit of the translatory movement of the shaft 73, in this way providing a safety feature which prevents jamming or other damage or breakage of the riveter in the event of failure of the limit switches or deflection switch, forming part of the electric control circuits of the apparatus of Figures 5 to 9, to operate.

The modified apparatus of Figure 5 has a forward limit switch 83 and reverse limit switch 84, which are conveniently mounted on top of the shelf 85 on the pedestal 73. This apparatus is also provided with a time switch 86 and a deflection switch 87 (see Figures 5, 8, 9, and 11). A screw having a disk or button 88 on one end is adjustably secured on the end of the translating-screw or shaft 73 so as to engage with and open the switches 83 and 86, and the switch 84. The deflection switch 87, which is mounted in the hollow jaw 3, is operated by deflection of the jaws 2 and 3 of the riveter frame under the force applied thereto in the riveting operations.

The extreme backward or retracted position of the rivet set 7 and translating screw 73 is governed by adjustment of the disk 88 relative to the end of the screw 73 and the forward movement or stroke of the rivet set 7 and translating-screw 73 may be varied by adjusting the switches 83 and 86 relative to the reverse limit switch 84 which is fixed to the shelf 85. An adjusting screw 89 on the base 90 for the forward limit switch 83 and time switch 86, (the base 90 being movable on the shelf 85) and the counterhand nut 91 rotatably secured on the shelf 85 provides means for adjusting the base 90 and its switches on the shelf 85 and for holding the switches 83 and 86 in adjusted position relative to the switch 84.

The deflection switch 87 is provided with a lever 92 which is pivoted on the free end of a U-shaped arm 93, this being conveniently made of wrought metal pipe or being positioned within the hollow frame A of the riveter, with one end rigidly fastened to the upper end of the jaw 3 of the riveter

frame. (See Figure 5.) A screw threaded rod 94 adjustably secured by nuts 95, 96 to a boss 97 on the jaw 3 is pivotally connected to the lever 92, the lever 92 being pivoted at one end to the free end of the U-shaped arm 93. The contacts of the switch 87 are attached, one to the free end of the lever 92 and the other to the jaw 3 of the riveter frame, and a coil spring 98 holds the contacts in engagement until springing movement or deflection of the frame jaws 2 and 3 causes relative movement of the upper end of the U-shaped arm 93 and jaw 3 and opens the switch 87 to break the motor control circuit.

The motor operating and control circuits for the riveter of Figures 1 and 2, (shown diagrammatically in Figure 10) comprises a series field 100, shunt field 101 and dynamic braking resistance 102, the shunt field being connected across the operating circuits so as to always be energized when current is on the motor operating circuits. The operating circuits also have magnetic switches 103 and 104, 105 and 106, and the overload relay 107. (In the apparatus shown in Figures 1 and 2 a deflection switch is not used.) A main switch 108 is employed to connect the positive and negative wires of the current supply line to the corresponding wires 109 and 110 of the motor operating circuits.

The motor control circuits are provided with the closed contact forward limit switch 55, a similar reverse limit switch 56, and a master switch or controller 111 by which the motor is reversed and is stopped in the operation of the apparatus.

In the wiring system for the apparatus of Figures 5 to 9, (illustrated in Figure 11) the motor operating circuits include a series field 100, shunt field 101, and dynamic braking resistance 102. (The shunt field is connected across the operating circuits in the same manner as in the wiring system of Figure 10.) Also included in the operating circuits are magnetic switches 103 and 104, magnetic switches 105 and 106, an overload relay 107, and in addition the magnetic switch 88, which is controlled by the mechanically operated deflection switch 87 and forward limit switch 83. The plus and minus wires 109, 110, of the circuits are connected through a main switch 108 to the wires forming the current supply line.

The operation of the device of Figures 1 to 4 referring to the wiring diagram of Figure 10 is as follows—

It will be assumed that the main switch 108 is in closed position, and the ram 8 is in retracted position in readiness to be advanced through its forward or working stroke. The work to be riveted or otherwise operated upon will be positioned between the dies 6 and 7.

The controller 111 will be in "off" or

open position, and the movable contact of the reverse limit switch 54 will be held open.

The bar 112 of the controller will be moved manually from its off position into a position to bridge the contacts 113 and 114, and when in this position a control circuit is completed from the positive wire 109 of the motor operating circuits, through the wire 115, the forward limit switch 55, the contacts 114 and 113, the wire 113^a to a point 113^b, from 113^b parallel control circuits proceed one through a wire 113^c and one through 113^d. The circuit through wire 113^c proceeds through the holding coil 107^a of overload relay 107, then to negative wire 110, and the circuit through wire 113^d proceeds through the closing coil 106^a of the magnetic switch 103, through wire 103^b, through the contacts 116, 117 of the overload relay 107, the operating coil 105^a of the magnetic switch 105, and to the negative wire 110 of the motor operating circuit, thus completing the control circuits which close the switches 105 and 103.

23 The closing of switch 105 opens switch 119, therefore, the motor operating current will flow from wire 109 through series field 100, wire 100^a, overload relay 107, switch 105, and wires 150, 150^a to motor armature 40.

24 From the armature 40 the current proceeds through wire 151, through switch 106, to negative wire 110. The shunt field 101, as has been said before, is across the line at all times after the main switch 108 is closed.

25 The circuit being completed the motor armature 40, of the motor, will be caused to rotate to turn the armature shaft 36 and nut 48 so as to move the translatory element or ram 8 and rivet set 7 through the forward working stroke. As the ram 8 reaches the limit of its forward stroke the notch 32 will align with the stem 56 of the switch 55 and allow it to move vertically, thereby breaking the control circuit to the switches 105 and 106 and allowing said switches to open, thereby breaking the circuit to the motor armature.

26 In the event of the limit switch 55 failing to function or for other reasons the pressure exerted by the ram and rivet set or translatory rivet set exceeding a predetermined maximum, the current value will rise so as to open the overload relay 107 and break the control circuit, thereby causing switches 105 and 106 to open and break the motor operating circuit.

27 As the switch 105 is opened the switch 119 is closed, and switch 119^a being already closed, the dynamic brake resistance 102 will be cut in on the motor, thereby preventing the reversal of the motor armature by the reaction from the rams of the machine.

28 After the motor stops the controller is moved into position to bridge the contacts 120 and 121 of the controller. When in

this position, the bar completes a control circuit from the positive wire 109, through wire 115, the reverse limit switch 54, bridged contacts 120, 121, operating coil of the magnetic switch 104, operating coil of the magnetic switch 103, to negative wire 110. Completing this control circuit causes the magnetic switches 103 and 104 to close and completes a motor reverse operating circuit through the plus wire 109, series field 100, switch 104, wire 151, armature 40, wire 150^a, magnetic switch 103, wire 123, to minus wire 110, thereby rotating the motor in the reverse direction. This reverse movement of the motor retracts or moves the transitory work engaging element in its backward direction. As the element reaches the limit of its backward movement, the notch 31 will align with the stem 56 of the reverse limit switch 54 allowing said switch to open and the opening thereof breaks the control circuit to the coils of switches 103 and 104, causing said switches to open and break the motor operating circuit. The opening of switch 103 also closes the switch 119^a and completes a circuit through the switch 119^a, thereby cutting in the dynamic brake resistance 102.

29 The above cycle of operations is then repeated in operating the machine.

30 The operation of the apparatus of Figure 5, referring to the wiring diagram of Figure 11 is as follows—

31 It will be assumed that the main switch 108 is in open position, and the ram 64 is in retracted position, in readiness to be advanced through its forward or working stroke. The work to be riveted or otherwise operated upon will be positioned between the dies 6 and 7.

32 The controller 111 will be in "off" or open position, and the movable contact of the reverse limit switch 84 will be held open.

33 The switch 108 will close and immediately a control circuit will be established through wire 115, time switch 86, forward limit switch 83, wire 83^a, deflection switch 87, wire 87^a, holding coil 99^a of magnetic switch 99, wire 99^b to line 110, thus closing switch 99.

34 The bar 112 of the controller will now be moved manually from its "off" position into position to bridge the contacts 113 and 114, and when in this position a control circuit will be established from forward limit switch 83 through wire 115^a, the contacts 114 and 113, the wire 113^a to a point 113^b, from 113^b parallel control circuits proceed one through a wire 113^c and one through a wire 113^d. The circuit through wire 113^c proceeds through the holding coil 107^a of overload relay 107, then to negative wire 110, and the circuit through wire 113^d proceeds through the closing coil 106^a of the magnetic switch 103, through wire 106^b, through the contacts 116, 117 of the overload relay 107.

107, the operating coil 105^a of the magnetic switch 105, and to the negative wire 110, thus completing a control circuit which closes switches 105 and 106.

- 5 The closing of switch 105 opens switch 119. Therefore, the motor operating current will flow from wire 109 through series field 106, wire 103^a, magnetic switch 99, overload relay 107, switch 106, and wires 150, 150^a to motor armature 40. From the armature 40 the current proceeds through wire 151, through switch 106, to negative wire 110. The shunt field 101, as has been said before, is across the line at all times after 15 the main switch 108 is closed.

The circuit being completed through the motor armature 40, the motor will be caused to rotate to turn the shaft 78 so as to move the translatory element or ram and die or rivet set 7 through the forward or working stroke. As the ram reaches the limit of its forward stroke the disk 83 will open the forward limit switch 82 thus breaking the control circuit to the switch 99 allowing it to 25 open and break the motor operating circuit. If for any reason the pressure on the work should be sufficient to deflect the jaws of the riveter the deflection switch 87 will be caused to open, thus breaking the control circuit to the switch 99 and breaking the motor operating circuit the same as if the limit switch 83 were open. It will be noted, however, that with the opening of switches 30 83 or 87, the control circuit through time switch 86, the one side of switch 82, wire 115^a, etc. to the switches 105 and 103 is not broken, hence the dynamic brake is not cut in and the motor is left to be brought to rest by the resistance of the work operated 40 upon, advantage being taken of the torque on the armature 40, and the inertia or fly wheel effect of the mass formed by the rapidly rotating armature and associated revolving parts.

- 45 However, if the ram should move forward sufficiently to open the time switch 86, or the pressure exerted by the ram should exceed a predetermined maximum, so as to cause the current value to rise sufficiently to 50 open the overload relay 107, or the bar 112 of controller 111 to be moved to break the circuit through the contacts 114, 113, the control circuit to switches 105 and 106 will be broken and the switches caused to open, and 55 since the opening of switch 105 closes the switch 119, and the switch 119^a being already closed, the dynamic brake resistance 102 will be cut in on the motor, thereby bringing it to a quick stop, and preventing 60 the reversal by the reaction from the rams of the machine.

After the motor stops the controller is moved into position to bridge the contacts 120 and 121 of the controller. When in this 65 position, the bar completes a control cir-

uit from the positive wire 109, through wire 115, one side of time switch 86, reverse limit switch 84, wire 84^a, bridged contacts 103, 121, operating coil of the magnetic switch 103, to negative wire 110. Completing this control circuit causes the magnetic switches 103 and 104 to close and complete a reverse motor operating circuit through the plus wire 108, series field 106, armature 40, wire 150^a, magnetic switch 105, wire 103, 70 to negative wire 110, thereby rotating the motor in the reverse direction. This reverse movement of the motor extracts or moves the translatory work engaging element in its backward direction. As the screw shaft of the translatory element reaches the limit of its backward travel, the disk 83 will contact with and open the reverse limit switch 84, thus breaking the control circuit to the switches 103, 104 and 75 causing them to open. The opening movement of switch 103 also closes the switch 119^a and completes a circuit through the switch 119^a, thereby cutting in the dynamic brake resistance 102.

The above cycle of operations is then repeated in operating the machine.

It is to be understood that while the drawings show preferred embodiments of the invention, various changes in the construction, arrangement and proportions of the parts may be resorted to in the adaptation of the invention to meet varying conditions without departing from the nature of the invention as defined in the appended claims.

I claim:

1. In a machine embodying fixed and translatory work engaging elements, an electric motor operatively connected to said translatory element, said translatory work engaging element being arranged to actuate limit switches to break the circuit to said motor after a predetermined extent of travel by said translatory element and the motor being adapted to supply the energy necessary to move said translatory work engaging element through said predetermined extent of travel, means for supplying current to said motor, and means for automatically breaking the circuit to said motor when the load on said motor exceeds a predetermined maximum.

2. In a machine embodying fixed and translatory work engaging elements, a motor for actuating the translatory element, a dynamic brake in circuit with said motor, an overload relay for breaking the circuit to said motor and operating said dynamic brake when the pressure of said work engaging elements exceeds a predetermined maximum, and an automatic deflection switch operated by the working pressure on said elements for breaking the circuit to said motor when a predetermined maximum pressure is exceeded.

3. In a machine embodying fixed and an open throat therebetween, a fixed die mounted in one of said stakes, a translating screw mounted in the other of said stakes, a movable die mounted in the forward end of said screw, an electric motor operatively connected to said screw and arranged to move said screw and the die mounted therein through a path of limited extent, an overload relay adapted to break the circuit to said motor when the load on said motor exceeds a predetermined maximum, and means for supplying current to said motor, an overload relay for shutting off the supply of current to said motor when the energy supplied said motor exceeds the predetermined maximum, and a yielding make and break device for breaking the circuit to said motor when the pressure on said work engaging elements exceeds a predetermined maximum.
4. In a machine embodying fixed and translatory work engaging elements, an electric motor operatively connected to said translatory element, means operated by said translatory work engaging element adapted to break the circuit to said motor when said element has moved a predetermined distance forwardly or rearwardly, a dynamic brake in circuit with said motor, and an overload relay adapted to break the circuit to said motor when the load on said motor is increased beyond a predetermined maximum and to cut in said dynamic brake so as to quickly stop said motor.
5. In a riveting machine embodying relatively movable work engaging elements, a translatory element, an electric motor for actuating said translatory element, an overload relay for breaking the circuit to said motor when the load on said motor exceeds a predetermined maximum, and means actuated by said translatory element for breaking the circuit to said motor when it has traveled a predetermined distance in its forward or reverse direction.
6. A riveter comprising a frame, fixed and movable dies, a translating screw carrying the movable die, an electric motor operatively connected to said screw and arranged to move said screw through a path of limited extent, an overload relay adapted to break the circuit to said motor when the load on said motor exceeds a predetermined maximum, and means controlled by the travel of said movable die for breaking the circuit to said motor when said screw exceeds said limited extent of travel.
7. A riveter comprising a U-shaped frame having its side stakes spaced apart forming

an open throat therebetween, a fixed die mounted in one of said stakes, a translating screw mounted in the other of said stakes, a movable die mounted in the forward end of said screw, an electric motor operatively connected to said screw and arranged to move said screw and the die mounted therein through a path of limited extent, an overload relay adapted to break the circuit to said motor when the load on said motor exceeds a predetermined maximum, and means controlled by the travel of said movable die for breaking the circuit to said motor when said screw exceeds said limited extent of travel.

8. A riveter comprising a U-shaped frame having its side stakes spaced apart forming an open throat therebetween, a fixed die mounted in one of said stakes, a translating screw mounted in the other of said stakes, a movable die mounted in the forward end of said screw, an electric motor operatively connected to said screw and arranged to move said screw and the die mounted therein through a path of limited extent, a dynamic brake in circuit with said motor, an overload relay adapted to break the circuit to said motor when the load on said motor is increased beyond a predetermined maximum and to cut in said dynamic brake so as to quickly stop said motor, and means controlled by the travel of said movable die for breaking the circuit to said motor when said screw exceeds said limited extent of travel.

In testimony whereof I have hereunto set my hand.

CHARLES J. WALKER.
